UNITED STATES PATENT OFFICE.

HENRY J. WIEGAND, OF MILWAUKEE, WISCONSIN, ASSIGNOR TO THE CUTLER-HAMMER MFG. CO., OF MILWAUKEE, WISCONSIN, A CORPORATION OF WISCONSIN.

GRID RESISTANCE.

942,156.

Specification of Letters Patent.

Patented Dec. 7, 1909.

Application filed March 29, 1909. Serial No. 486,513.

To all whom it may concern:

Be it known that I, HENRY J. WIEGAND, a citizen of the United States, residing at Milwaukee, in the county of Milwaukee and State of Wisconsin, have invented new and useful Improvements in Grid Resistances, of which the following is a full, clear, concise, and exact description, reference being had to the accompanying drawing, forming a part of this specification.

My invention relates to improvements in grid resistances.

As usually constructed, grid resistances consist of a long, reflexed bar, having a number of convolutions, and are more or less flimsy. To give such resistance grids the requisite strength, it is desirable to utilize a metal reinforcing member, substantially U-shaped in cross section, which is placed over the ends of the convolutions. The metal reinforcing members are, of course, insulated from the grid. Owing to the fact that the grids often become extremely hot during service and expand, the reinforcing members are loosened and have a tendency to drop off. With the usual forms of grid it is a difficult matter to securely fasten reinforcing strips thereto.

The object of my invention is to provide a grid having portions designed to be engaged by portions of the reinforcing members so that said members will be held thereon under all conditions of service.

In order that my invention may be thoroughly understood I have illustrated the preferred form thereof in the accompanying drawings.

In the accompanying drawings.—Figure 1 is an elevation of a grid resistance embodying my invention; Fig. 2 is an end view of a portion of the grid showing the means of securing a reinforcing member in position, and Fig. 3 is an enlarged perspective view of one corner of the grid, showing the reinforcing member with one corner bent into position.

In the embodiment of my invention, as shown in the drawing, I provide a grid resistance A, consisting of a reflexed strip or bar having a number of convolutions a. The outer bars a' are preferably of the same length as the intermediate bars and are provided with suitable terminals a'', by means of which the grid may be fastened in po-

sition and electrically connected in circuit. 55 The outer bars are provided at or near their ends with lugs a''. Said lugs a'' are preferably provided with an inclined face a', for a purpose hereinafter set forth.

Over the edges of the grid, on opposite sides, or, in other words, over the ends of the bars or convolutions, I place reinforcing strips B, preferably substantially U-shaped in cross section. Each of the reinforcing strips is preferably provided with one or 65 more ribs or beads b', which are stamped up therefrom to strengthen it transversely. Between each of the reinforcing strips and the grid, I interpose an insulating strip C, made of any suitable material, to insulate 70 the reinforcing strips from the grid. It is preferable to bend the sides of the reinforcing strips inwardly so as to tightly grip the grid.

In order to prevent the reinforcing strips 75 from becoming loose and dropping off, due to the expansion of the grid when heated, the corners of the reinforcing and insulating strips are bent inwardly, as at b'', so as to engage the surface a' of the lugs a''. The 80 reinforcing strips are thus firmly held in place and can only be removed after the corners b'' have been bent outwardly out of engagement with the lugs.

By providing the lugs with an inclined 85 face a', as shown in the drawing, it is much easier to bend the corners of the reinforcing member thereover than if the lugs were of other form. However, I desire it to be understood that the lugs may assume any desired form. 90

Having thus described my invention, what I claim as new and desire to secure by Letters Patent, is:—

1. In combination, a grid resistance having lugs thereon, and a reinforcing strip placed over the edge of said grid and having portions bent around said lugs to retain the same on said grid. 95

2. In combination, a grid resistance having lugs formed on the end bars thereof, substantially U-shaped reinforcing strips placed over the edges of the grid, said reinforcing strips having portions thereof bent around said lugs. 100

3. In combination, a grid resistance having lugs formed on the end bars thereof, said lugs having an inclined face, reinforc-

- ing strips placed over the edges of said grid and having portions bent over the inclined faces of said lugs, and means for insulating the reinforcing strips from the grid.
- 5 4. In combination, a grid resistance having lugs formed on the end bars thereof, substantially U-shaped reinforcing strips placed over the edges of said grid, and insulating strips interposed between said reinforcing strips and said grid, said reinforce-
- 10

ing and insulating strips having portions thereof bent around said lugs.

In witness whereof, I have hereunto subscribed my name in the presence of two witnesses.

HENRY J. WIEGAND.
